UNITED STATES PATENT OFFICE.

ALBERT J. VER BRYCK, OF NEW YORK, N. Y.

DESIGN FOR A SANITARY SUITCASE-CAN.

48,477.

Specification for Design.

Patented Jan. 18, 1916.

Application filed May 6, 1915. Serial No. 26,432. Term of patent 7 years.

To all whom it may concern:

Be it known that I, ALBERT J. VER BRYCK, a citizen of the United States, and residing at 725 East One Hundred and Sixty-third street, in the city of New York, county of New York, and State of New York, have invented a certain new, original, and ornamental Design for a Sanitary Suitcase-Can, fully described and represented in the following specification and the accompanying drawings, forming a part of the same.

Figure 1 is a perspective view, Fig. 2 is an elevation of the right hand end and Fig. 3 an elevation of the left hand end of the can showing my new design.

I claim:

The ornamental design for a sanitary suit-case can, as shown.

In testimony whereof I have hereunto set my hand.

ALBERT J. VER BRYCK.
